MASONIC NECK ORNAMENT

Charles S. Cowell, Osborn, Mo.

Application July 11, 1955, Serial No. 36,889

Term of patent 7 years

(Cl. D3—16)

I claim:

The ornamental design for a Masonic neck ornament, substantially as shown.
